Patented Mar. 8, 1966

204,040

COAT HANGER UNIT

Shirley McLarty, 417 Blanning St., Dallas County, Tex.

Filed Sept. 22, 1964, Ser. No. 81,830

Term of patent 14 years

(Cl. D80—8)

FIG. 1

FIG. 3

FIG. 1 is a front elevational view of a coat hanger unit embodying my new design;

FIG. 2 is a side elevational view thereof; and

FIG. 3 is a bottom plan view thereof.

I claim:

The ornamental design of a coat hanger unit as shown, and described.
